US0D1063989S

(12) **United States Design Patent** (10) **Patent No.:** **US D1,063,989 S**
(45) **Date of Patent:** **** Feb. 25, 2025**

(54) **SHAFT AND GEAR HOUSING**

(71) Applicant: **David H. Vroom**, Tucson, AZ (US)

(72) Inventor: **David H. Vroom**, Tucson, AZ (US)

(**) Term: **15 Years**

(21) Appl. No.: **29/924,260**

(22) Filed: **Jan. 18, 2024**

(51) LOC (15) Cl. **15-01**

(52) U.S. Cl.

USPC **D15/5**

(58) **Field of Classification Search**

(57) **CLAIM**

The ornamental design for a shaft and gear housing as shown and described.

DESCRIPTION

FIG. 1 is a first perspective view of the design;
FIG. 2 is a second perspective view of the design;
FIG. 3 is a first side elevational view thereof;
FIG. 4 is a second side elevational view thereof;
FIG. 5 is a top plan view thereof;
FIG. 6 is a bottom plan view thereof;
FIG. 7 is a third side elevational view thereof; and,
FIG. 8 is a fourth side elevational view thereof.

1 Claim, 7 Drawing Sheets
